UNITED STATES PATENT OFFICE

2,578,864

SEAL FOR FLEXIBLE CONTAINERS

Earl S. Tupper, Upton, Mass.

Application December 1, 1948, Serial No. 62,845

1 Claim. (Cl. 222—206)

1

This invention relates to perfume, powder and medicant dispensers.

It is an object of the present invention to provide a perfume, powder and medicant dispenser wherein the perfume or powder is contained in a chamber of flexible and resilient material which is squeezed to effect a dispensing action and wherein upon being released will be returned instantly to its original shape and wherein the dispensing device serves as the packaging container in which the contents are delivered to the consumer and wherein the container is made usable as a dispensing device by the breaking of an integral tip of the material.

It is another object of the present invention to provide for a dispensing device of the flexible chamber type a suitable base for retaining the open end of the chamber and for providing sufficient backing of the chamber wall within the base whereby to prevent leakage which might result when the chamber is squeezed or a breaking down of the base connection after constant use.

Other objects of the present invention are to provide a resilient chamber dispenser for perfume, powder and the like which is of simple construction, easy to assemble, easy to prepare for use, tightly sealed, inexpensive to manufacture, convenient to use and efficient in operation.

For other objects and for a better understanding of the invention, reference may be had to the following detailed description taken in connection with the accompanying drawing, in which

Figure 1 is a perspective view of the resilient dispensing device embodying the features of the present invention.

Figure 2 is a sectional view, in elevation, taken on line 2—2 of Figure 1.

Figure 3 is a side elevational view of a dispenser particularly adapted for dispensing powder, the dispenser being held and squeezed for dispensing action.

Figure 4 is an enlarged sectional view taken through the connection of the base with the resilient chamber and showing the reinforcing member for the inner wall of the chamber, the view being taken on line 4—4 of Figure 1.

Figure 5 is a fragmentary sectional view taken through the connection of the tube with the dispensing end of the flexible chamber of the form of the invention shown in Figures 1 and 2, the view being taken on line 5—5 of Figure 2.

Figure 6 is a fragmentary sectional view of a modified form of the device shown in Figure 1 wherein a projection for nasal introduction is provided for use of the device as a nasal spray.

2

Referring now to the figures, 10 represents a resilient or flexible chamber adapted to contain perfume or a medicant 11 which is normally closed at its upper end as when the perfume is being delivered from the factory to the consumer and which is especially formed with a tip 12 having a hole 13. To prepare the device for use, the tip 12 is severed to open the hole 13.

Depending from the top and below the hole 13 is a hollow portion 14 adapted to receive a tube 15 which is curved at its lower end and which extends to the bottom of the device. The depending portion 14 is formed with side passages 16 through which air may pass through the opening 13 when the squeezing action is effected upon the chamber to draw the perfume through the tube 15 and to eject the same into the atmosphere.

The bottom end of the chamber 10 is formed with a flange 17 from which depends a skirt portion 18. This skirt portion is threaded as at 19 to receive and retain a base 21 of rigid material. The lower end of the portion 18 is not threaded and extends into a peripheral recess 22 formed in the base whereby to provide support for the lower end of the portion 18 and to prevent the same from moving inwardly. In order to be certain of the connection of the resilient chamber with the base and to provide adequate sealing action, there is provided adjacent the threads 19 but on the inner wall of the chamber a recess 23 receiving a depending flange 24 of a bottom reinforcing member 25. This member 25 with flange 24 will positively retain the depending portion 18 within the base and will maintain the portion 18 in tight sealing engagement with an external and upstanding threaded flange or portion 26 threaded onto the threads 19.

It will be apparent that there is little opportunity for the portion 18 to free itself of the base. The lower end of the flange 24 of the reinforcing member 25 will press the lower end of the depending portion 18 into the recess 22. It will be seen that a positive sealing action is effected. The upper end of the portion 26 will abut the flange or shoulder 17.

As shown in Figure 6, an orificed nasal projection 27 is formed as the top of chamber 10 with a removable tip 28 similar to 12.

The chamber 10 is formed of a plastic material which when released will return to its original shape instantly. The members 21 and 25 are preferably formed of a more rigid plastic.

In Figure 3, there is shown a slightly different type of chamber wherein there is provided a plurality of openings 27 on the top thereof for the

purpose of dispensing a powder or granular material 28. The same operation is performed upon the chamber as when dispensing a liquid such as perfume as with the form of the invention above described. The same seal is effected upon the bottom of the chamber.

While various changes may be made in the detail construction, it shall be understood that such changes shall be within the spirit and scope of the present invention as defined by the appended 10 claim.

I claim:

A dispensing device comprising a resilient squeeze chamber having a dispensing opening at its upper end, said chamber having a depending skirt portion partly threaded and free of threads on its lower end, a base having a peripheral groove adapted to receive the lower end of the depending portion of the chamber, said base having an upwardly extending internally threaded peripheral portion against which the depending portion of the chamber may be depressed, a reinforcing member fitted within the chamber and serving to urge the depending portion into the recess of the base and against the upwardly extending portion thereof, said reinforcing member having a peripheral depending portion, said resilient

squeeze chamber having an internal recess, said peripheral depending portion of the reinforcing member lying within the recess, the lower end of the peripheral depending portion of the reinforcing member extending over the groove of the base to retain the part of the depending portion of the resilient squeeze chamber therewithin.
